Des. 241,584
Patented Sept. 21, 1976

241,584

ELECTRIC SHAVER

Hermann R. Schaefer, Bridgeport, Conn., assignor to
Sperry Rand Corporation, Bridgeport, Conn.

Filed Feb. 24, 1975, Ser. No. 552,634

Term of patent 14 years

Int. Cl. D28—03

U.S. Cl. D95—3 A

Fig. 1

Fig. 2

Fig. 5.

Fig. 4.

Fig. 3.

FIG. 6.

FIG. 7.

FIG. 8.

FIG. 1 is a perspective view of the rear and right side of an electric shaver showing my new design;

FIG. 2 is a perspective view of the electric shaver of FIG. 1 showing in particular the front of the shaver;

FIG. 3 is an elevational view of the left side of the shaver of FIG. 1;

FIG. 4 is an elevational view of the front of the shaver of FIG. 1;

FIG. 5 is an elevational view of the right side of the shaver;

FIG. 6 is an elevational view of the rear of the shaver;

FIG. 7 is a top plan view of the shaver appearing in FIG. 6; and

FIG. 8 is a bottom plan view of the shaver as seen in FIG. 6.

I claim:

The ornamental design for an electric shaver, substantially as shown.
